(57) CLAIM

The ornamental design for a combination dog leggings and suspenders as shown and described.

DESCRIPTION

FIG. 1 is a front perspective view of a combination dog leggings and suspenders, showing my new design;

FIG. 2 is a rear perspective view thereof;

FIG. 3 is a front elevational view thereof, the rear elevational view being a mirror image of FIG. 3;

FIG. 4 is a left elevational view thereof;

FIG. 5 is a right elevational view thereof;

FIG. 6 is a top plan view thereof;

FIG. 7 is a bottom plan view thereof;

FIG. 8 is an enlarged, perspective view of detail “8”, identified in FIG. 1; and,

FIG. 9 is an enlarged, perspective view of detail “9”, identified in FIG. 2.

In the drawings, the broken lines depict portions of the combination dog leggings and suspenders that form no part of the claimed design.
